UNITED STATES PATENT OFFICE.

EDWARD F. FISHER, OF SEATTLE, WASHINGTON.

HOSE-RACK.

No. 926,556.

Specification of Letters Patent. Patented June 29, 1909.

Application filed February 26, 1909. Serial No. 480,191.

To all whom it may concern:

Be it known that I, EDWARD F. FISHER, a citizen of the United States, residing at Seattle, in the county of King and State of Washington, have invented new and useful Improvements in Hose-Racks, of which the following is a specification.

This invention relates to hose racks, the object of the invention being to provide a simple and convenient portable and folding rack for supporting a hose in position to effect a thorough draining of the same after use, also enabling the hose to be easily removed from the rack when required. The rack is either adapted to support itself in position on a floor or to be hung against a wall or other vertical support.

With the above and other objects in view, the invention consists in the novel construction, combination and arrangement of parts as herein fully described, illustrated and claimed.

In the accompanying drawings: Figure 1 is a perspective view of a rack constructed in accordance with the present invention, showing a hose supported thereon, the uprights of the rack being spread apart so that the rack will be self-supporting. Fig. 2 is an end elevation of the rack, showing the runs of the hose in section. Fig. 3 is a view of the rack folded, the hose being omitted.

The rack contemplated in this invention comprises two sets of parallel uprights, 1 designating the uprights at one side of the rack and 2 the similar uprights arranged at the opposite side of the rack. The uprights 1 and 2 are pivotally connected adjacent to their upper ends, all of said uprights being connected by preference to a pivot 3 as shown, the pivot rod 3 also acting as a tie rod for the upper part of the rack. The uprights are further connected by cleats 4 which also act to tie the uprights at each side of the rack together as clearly shown in Figs. 1 and 2, thus forming a perfectly braced structure embodying two similar sides, which are pivotally connected together along the top. The cleats 4 act as supports for the hose indicated at 5 and it will be noted that said hose supporting cleats are arranged in reversely inclined order or in zigzag relation so that the different runs of the hose incline reversely and give a downward inclination to the entire

length of hose from the top of the rack to 55 the bottom thereof. It will also be noted that the cleats 4 are of greater thickness than the diameter of the hose so that staples 6 or the like may be driven into the upper sides of the cleats near the ends thereof to 60 hold different portions of the hose in place.

The different runs of the hose are also held detachably on the rack and in engagement with the supporting cleats by means of turn buttons 7 secured to the end uprights as shown in Figs. 1 and 2, said buttons being arranged just over the cleats so as to overhang the runs of the hose and retain the hose in engagement with the upper edges of the cleats 4.

The rack is adapted to stand upon the floor and be self-supporting by moving the lower ends of the uprights apart as shown in Fig. 1. The uprights 1 and 2 may also be folded into parallel relation as shown in Fig. 3 to enable the device with the hose thereon to be easily moved from place to place or hung upon the wall or other support.

The hose is removed from the rack by taking hold of the end of the hose or pulling 80 on the same, which causes the button 7 to turn and release its hold on the hose; at the same time this movement of the hose causes it to slip out from behind the staple 6. This operation is continued until the entire 85 length of hose is detached from the rack.

I claim:

1. A rack of the class described comprising two sets of uprights pivotally connected together at their upper ends, hose-supporting cleats connected to said uprights and arranged in reversely inclined order, and turn buttons arranged adjacent to said cleats, substantially as described. 90

2. A rack of the class described comprising two sets of uprights pivotally connected together at their upper ends, hose-supporting cleats connecting said uprights and arranged in reversely inclined order, staples on the cleats for retaining the runs of the hose in 100 position, and turn buttons for holding the hose in engagement with said cleats.

In testimony whereof I affix my signature in presence of two witnesses.

EDWARD F. FISHER.
